FIGURE 1 is a side elevational view of one side of a combined butt cap and measuring tape for fishing rod handles, showing my new design;

FIGURE 4 is a side elevational view of the other side; and,

The broken line showing of the fishing rod is for illustrative purposes only.

I claim:

The ornamental design for a combined butt cap and measuring tape for fishing rod handles, as shown and described.
